UNITED STATES PATENT OFFICE.

THEODORUS H. PATEE, OF GREENCASTLE, INDIANA.

COUPLING FOR LIGHTNING-RODS.

SPECIFICATION forming part of Letters Patent No. 297,290, dated April 22, 1884.

Application filed November 1, 1881. (No model.)

To all whom it may concern:

Be it known that I, THEODORUS H. PATEE, a citizen of the United States, residing at Green-
castle, in the county of Putnam and State of
Indiana, have invented certain new and useful
5 Improvements in Couplings for Lightning-
Rods; and I do hereby declare the following
to be a full, clear, and exact description of
the invention, such as will enable others skilled
10 in the art to which it appertains to make and
use the same, reference being had to the accom-
panying drawings, and to the letters or fig-
ures of reference marked thereon, which form
a part of this specification.

15 My invention relates to lightning-rods; and
the object of my improvement is to produce a
new method of attaching the coupling-sections
to the cast-metal ends of the spirally or other-
wise formed intermediate sections of such rods.
20 This is an improvement on the invention for
which Letters Patent No. 257,890 were formerly
issued to me. I attain this object sought by
the method illustrated in the accompanying
drawings, in which—

25 Figure 1 is an elevation showing parts of
two sections of a lightning-rod of the usual
spiral form with a part of the coupling-section
attached to each, the parts being sepa-
rated for the purpose of showing how the two
30 parts of the coupling-section are united. Fig.
2 is a sectional elevation of one of the parts of
the coupling-section as it appears when finished
and ready for use in connection with the screw-
threaded intermediate section. Fig. 3 is a
35 sectional elevation of one part of the coupling-
section as it appears when ready to be applied
to an intermediate section, the end of which
is cylindrical in form, but largest at its inner
end. Fig. 4 is an end view of the parts shown
40 in Figs. 2 and 3. Fig. 5 is an elevation, partly
in section, of a portion of one, showing the
intermediate or spiral sections of the rod
having the tenon or projection *a* upon its end
enlarged at its outer end, and as it appears
45 when the coupling-section has been swaged
or pressed down upon it. It also shows a
cross-section of the coupling part; and Fig. 6
is an elevation, partly in section, of a portion
50 of one part of a coupling-section, and showing
in elevation a portion of a spirally-formed
intermediate section having a tenon or pro-

jection with ribs on it, its outer end being the
largest, and the coupling part swaged down
upon it, a cross-section being also shown.
Fig. 7 shows in vertical section the coupling 55
or joint of rod before being compressed.

Similar letters refer to similar parts in the
several views.

It has been customary heretofore to secure
the portions of the coupling-sections of light- 60
ning-rods to the intermediate or spiral sec-
tions in various ways, usually by screwing
them onto said intermediate sections or by
riveting them thereto; but these methods have
been found more or less objectionable, on ac- 65
count of the amount of labor required in the
process.

In securing coupling-sections to the inter-
mediate parts by my improved method, I pre-
pare the ends of the spirally or otherwise 70
formed sections of the rods by forming thereon
a straight cylindrical portion and cutting a
thread thereon, as shown at A A' in Fig. 7.

For the reception of the screw-threaded
tenon or projection there are formed in the 75
parts B B' of the coupling-sections holes the
diameters of which are sufficiently large to
admit of the threaded tenon being passed into
it without having any screw-thread in the
coupling parts. The tenons are passed into 80
these holes, when, for the purpose of holding
the parts firmly together and preventing them
from turning one upon the other, the coup-
ling parts (which are to be made of cast
metal sufficiently malleable to admit of its 85
being done) are to be swaged, hammered, or
pressed down upon the screw-tenon, the effect
of which is to cause a portion of the metal
composing the coupling-sections to be em-
bedded in the thread of the tenon, which will 90
secure the parts of the coupling-section firmly
thereto.

The swaging, hammering, or pressing is best
done when the parts of the coupling-sections
are in the condition shown in Figs. 3 and 4 95
of the drawings, after which they can be turned
or milled and have a screw-thread formed on
them, as shown in Fig. 2, for the purpose of
uniting them to the parts B, which have had
a female screw-thread formed in them, after 100
having been treated in the same manner, so
far as the method of fastening them upon the

intermediate sections is concerned, as those already described.

It is evident that screw-threads may be formed on the inside of the dovetail couplings.

5 Instead of using the straight cylindrical tenon on the intermediate sections of the rod, as above described, the parts may be united by forming upon said intermediate parts a tenon of the form shown in Fig. 5, it being 10 largest at its outer end, as there shown, and forming in the parts B B' apertures large enough to permit the tenons to be passed into them, and then swaging, hammering, or pressing the parts of the coupling-sections down 15 thereon, as above described, when the parts will assume the form shown in the figure last alluded to, and their separation be effectually prevented.

Another modification of my method is shown 20 in Fig. 6, which is intended to provide for securing the parts together without forming a cylindrical tenon or projection upon the ends of the intermediate sections, and thus providing for attaching the coupling-sections to 25 the intermediate ones when of a spiral or any other flanged form. This modification contemplates the preparation of the coupling-sections by forming in them apertures for the reception of the ends of the intermediate sec-

tions, as above described, and then turning 30 or cutting off a portion of the outer surface of the flanges or of the rod, as shown, and thus forming a tenon largest at its outer end, upon which the metal of the coupling parts may be swaged, hammered, or pressed, as 35 above described.

Having thus described my invention, what I claim, and desire to secure by Letters Patent, is—

1. The lightning-rod joint consisting of the 40 dovetailed tenons on the ends of the rod-sections, in combination with the coupling-pieces B B', provided with screw-threads, and with projecting portions for clasping the ends of the rod, as shown and described.

2. The lightning-rod joint consisting of 45 threaded tenons as shown, in combination with the internally-threaded coupling-pieces of larger diameter than said tenons, whereby the coupling-pieces are adapted to fit loosely on 50 said tenons and to be secured, as described.

In testimony whereof I affix my signature in presence of two witnesses.

THEODORUS H. PATEE.
